UNITED STATES PATENT OFFICE

CARL L. WILLARD, OF LYNWOOD, CALIFORNIA, ASSIGNOR TO TRANSIT MIXERS INC.
A CORPORATION OF NEVADA

MIXING OR AGITATING DEVICE

Application filed November 23, 1928. Serial No. 321,305.

This invention relates to agitating or mixing devices designed for use in the transporting or conveying of the aggregates forming a concrete mixture.

It is designed to receive either wet or dry concrete batches and for operation to maintain the same in agitation if it is so desired during its transportation; also to prevent the separation or settling of the respective aggregates during transportation; to enable the supplying of a liquid to the dry batch when carried, to enable the aggregate to be mixed near its point of use after being transported to the point of liquid application in a dry state.

The invention is further designed to rotate at the will of the operator and is provided with mixing or agitating blades designed to agitate or mix the material on the rotation of the cylinder and to convey it to one end of the cylinder containing a discharge opening, when the cylinder is rotating in a predetermined direction.

The invention also affords a structure wherein the cylinder may be rotated in either of two directions from a point of rest, to afford a quick, efficient, uniform and economical intermixing of the aggregate. In addition to the above objects and advantages, the invention affords a structure wherein a single chute adjustable for different positions serves to deliver material into the cylinder and to convey material therefrom.

In accomplishing the above objects, the invention is designed so that the cylinder remains in substantially horizontal position during all operations, and is not tipped or inclined rearwardly during the material discharging operation.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein—

Fig. 1 is a view in side elevation of one embodiment of the invention. Fig. 2 is a vertical section on line 2—2 of Fig. 1. Fig. 3 is a view in detail of the cylinder illustrating the spiral conveyer therein. Fig. 4 is a fragmentary view of a cylinder having a conical end into which extend the trough shaped blades. Fig. 5 is a view in detail of one of the blades in Fig. 4. Fig. 6 is a longitudinal sectional view of a cylinder, having a plurality of concentrically arranged spiral conveyers therein, pitched in opposite directions.

In the drawings, wherein like characters of reference designate corresponding parts, 1 indicates a vehicle chassis driven by the power plant beneath the hood 2, which transmits to wheels 3 through transmission 4. On the supplemental frame 5 resting on main frame 6 is a mixing cylinder 7 mounted to rotate on a horizontal axis in the cradles 8, the latter being provided with anti-friction cylinder supporting rollers 9. The rear end wall 10 of the cylinder 7 is provided centrally with an opening 11 controlled by a gate or closure 12, and the forward end wall is provided with an opening through which extends the valve controlled pipe 13 leading from water tanks 14 carried by the cradles 8.

The cylinder 7 carries a ring gear 15 with which engages a pinion 16 on a shaft 17 extended from a power take-off 18, of any well known type, associated with the transmission gear box 19. The power take-off is of that type capable of driving the shaft in either of two directions, or permitting the same to remain idle when desired. The selective operation of the power take-off is controlled by the operation of a shaft lever 20 connected with lever 21 to move the same from N (neutral position) to either R (right) or L (left) drive position.

On its interior the cylinder is provided with a screw conveyer or worm 22 adapted on the rotation of the cylinder in one direction to convey the material toward the forward end and to convey it toward the opposite end on the rotation of the cylinder in a reverse di-

rection, agitation taking place during both operations.

To discharge the mixed aggregate from the cylinder while the cylinder remains in a substantially horizontal position, and is rotated to cause the conveying of the material toward the rear end wall 10, I provide a trough or chute 23 mounted to pivot on a horizontal axis between the free ends of arms 24 pivotally mounted at corresponding ends to the cradle frames. A member 25 extending upwardly alongside of cylinder 7 is provided with arm supporting stops 26 for supporting the arms 24 in either of three positions, indicated at A—B—C—Fig. 1. A spring held locking pin 27 carried by arm 24 and cooperating with recesses in an arcuate flange 28 on the side wall of the chute 23 retains the chute in its pivotally mounted position D—E—F. The chute or trough is pivoted to position D with the arms 24 in position A, when these parts are in normal inoperative position, as illustrated in full lines—Fig. 1. When it is desired to deliver aggregate into the cylinder through the opening 11, the arms 24 are moved to position B with the chute in position E, the chute being inclined downwardly into the opening 11 with its end extended thereinto. To convey the mixture from the cylinder while the same is in a substantially horizontal position, it is first necessary to operate the power take-off to rotate the cylinder so that worm 22 conveys the material toward the rear end of the cylinder. During this operation, the arms 24 are moved to position C and chute 23 is adjusted to position F, the same assuming a downward inclination from the rear of the cylinder, with the inner end of the chute extended a distance into the opening to receive the material as it is picked up by screw 22 and drops vertically therefrom across the opening.

It will be apparent that the discharge of the material from the cylinder is accomplished while the same is in a substantially horizontal position and without inclining the same rearwardly; also that the cylinder is rotated in either or both of two directions during the agitating or mixing of the material; also that the chute is movable to afford a means for filling the cylinder as well as removing material therefrom.

In the Fig. 4 disclosure, the end of the cylinder 7 is of conical formation provided with an opening 29 adaptable for closing by a removable cover 30. The spiral conveyer on the interior of the cylinder terminates adjacent to the opening 29 in relatively deep wide trough shaped blades 31, disposed at a sufficient angle that when the cylinder is rotating in discharge direction, the aggregate picked up by said blades will slide longitudinally thereof and discharge from the cylinder through the opening 29 when the cover 30 is removed. This type of structure enables

the trough shaped blades to discharge the material through the opening and clear of the mixer automatically and while the cylinder is in horizontal position. However, if it is so desired, the chute 23 or similar structure may be provided to convey the discharged aggregate to any suitable point.

The cylinder may be constructed with a plurality of spiral conveyers 32 and 33, pitched in opposite directions and arranged one concentrically of the other. With this structure, the inner conveyer 32 agitates the aggregate near the surface of the mass within the cylinder, and conveys it in one direction and the outer conveyer 33 agitates the material near the bottom of the mass and conveys it in another direction. Thus the aggregate is moving in a plurality of directions longitudinally of the cylinder, regardless of its direction of rotation, and when the cylinder is rotating in a direction for the spiral to convey the aggregate toward the discharge opening, this movement will be readily accomplished. The conveying of the aggregate from the discharge opening will gradually reduce the volume thereof within the cylinder until its level will be at a point below the action of the conveyer 32.

I claim:

1. A mixing device comprising a horizontal rotatable cylinder provided with a discharge opening at one end, a closure for said opening, a plurality of spiral conveyers pitched in opposite directions and arranged concentrically of each other within the cylinder, means for rotating the cylinder in either of two directions to cause the conveyers to move the material in continuous layers travelling reversely to each other to and from said discharge opening depending on the direction of rotation of the cylinder and while the cylinder is in substantially horizontal position, and means for cooperating with the discharge opening for directing material therefrom, dependent on the direction of rotation of the cylinder.

2. A mixing device comprising a horizontal rotatable cylinder provided with a discharge opening at one end, a closure for said opening, a plurality of spiral conveyers pitched in opposite directions and arranged concentrically of each other within the cylinder, means for rotating the cylinder in either of two directions to cause the conveyers to move the material in continuous layers travelling reversely to each other to and from said discharge opening depending on the direction of rotation of the cylinder and while the cylinder is in substantially horizontal position, and means for cooperating with the discharge opening for removing material from the cylinder on a rotation of the cylinder in a direction to cause one of the conveyers to convey the material toward said discharge opening.

3. The combination in a transit mixer, of a rotatable cylinder provided with a filling and discharge opening at one end, a closure for said opening, a plurality of spiral conveyors pitched in opposite directions and arranged concentrically of each other within the cylinder, and power means for rotating the cylinder in either of two directions to cause the conveyors to move the material in continuous layers travelling reversely to each other from end to end of the cylinder. 70
4. The combination in a transit mixer, of a rotatable cylinder provided with a filling and discharge opening at one end, a closure for said opening, a plurality of spiral conveyors pitched in opposite directions and arranged concentrically of each other within the cylinder, a propelling power plant, and a power take-off means associated with the propelling power plant for operation to rotate the cylinder in either of two directions to cause the conveyors to move the material in continuous layers travelling reversely to each other from end to end of the cylinder. 75
5. The combination in a transit mixer, of a rotatable cylinder provided with a filling and discharge opening at one end, a closure for said opening, a plurality of spiral conveyors pitched in opposite directions and arranged concentrically of each other within the cylinder, means associated with the cylinder for conveying the material therefrom on its rotation in one of two directions, and means for rotating the cylinder in either of two directions to cause the conveyors to move the material in continuous layers travelling reversely to each other from end to end of the cylinder. 80
6. The combination in a transit mixer, of a rotatable cylinder provided with a filling and discharge opening at one end, a closure for said opening, a plurality of spiral conveyors pitched in opposite directions and arranged concentrically of each other within the cylinder, power means for rotating the cylinder to cause the conveyors to move the material in continuous layers traveling reversely to each other from end to end of the cylinder and finally to cause one of the conveyors to convey the material therein toward said filling and discharge opening while the cylinder is in substantially horizontal position, and means movable into and out of said opening for receiving the material so conveyed and for discharging it from the cylinder. 85
7. A mixing apparatus comprising a horizontal rotatable cylinder provided at one end in alignment with its axis of rotation with a discharge opening, a closure for said opening, means for rotating the cylinder in either of two directions, a plurality of spiral conveyors pitched in opposite directions and ar- 90
- ranged concentrically of each other within the cylinder for moving the material in continuous layers travelling reversely to each other from end to end of the cylinder, trough-shaped terminal blades disposed within the discharge end of the cylinder for effecting discharge thereof dependent on the direction of its rotation, and means for projection into the cylinder through said discharge opening for conveying material from the cylinder while the same is rotating in a substantially horizontal position. 95
8. A mixing device comprising a non-tiltable cylinder disposed in a substantially horizontal plane mounted for axial rotation and provided with a discharge opening at one end, a removable closure for said opening, a plurality of spiral conveyors mounted interiorly of the cylinder to rotate therewith, said spiral conveyors being pitched in opposite directions and arranged concentrically of each other, means for rotating the cylinder to cause the conveyors to move the material therein in continuous layers alternately towards opposite ends of said cylinder and to discharge the material from said opening on the removal of the closure therefrom. 100
9. A concrete mixing apparatus comprising a horizontally disposed elongated axially rotatable cylinder provided at one end with a discharge opening, a plurality of spiral conveyors concentrically disposed longitudinally within the cylinder to rotate therewith, said conveyors pitched in relatively opposite directions longitudinally of the cylinder and extending from end to end thereof, and means for rotating the cylinder in either of two directions to cause the conveyors to move the material in continuous layers travelling reversely to each other from end to end of the cylinder. 105
10. A mixing apparatus comprising a rotatable cylinder, a series of spiral conveyors concentrically disposed longitudinally within the cylinder to rotate therewith, said conveyors pitched in relatively opposite directions longitudinally of the cylinder, and means to rotate the latter to cause the conveyors to move the material in continuous layers travelling reversely to each other from end to end of the cylinder. 110
11. A mixing apparatus comprising a rotatable cylinder, a series of continuous spiral blades longitudinally disposed within the cylinder and rigidly secured to the walls thereof, a reversely pitched series of continuous spiral blades longitudinally disposed within said first mentioned series in rigid concentric relation thereto, one of said series adapted to longitudinally and continuously move the material in the cylinder in one direction and the other series adapted to longi- 115
